UNITED STATES PATENT OFFICE

SIDNEY J. BEERTHERMAN, OF CHEPACHET, RHODE ISLAND, ASSIGNOR TO L. & B. JEWELRY MANUFACTURING COMPANY, OF PROVIDENCE, RHODE ISLAND, A CORPORATION OF RHODE ISLAND

EXTENSION DEVICE

Application filed December 7, 1929. Serial No. 412,465.

My present invention relates to extension devices for flexible bracelets, and has particular reference to novel structure for retaining the extension devices in folded position.

One object of my invention is to provide a lock mechanism which stands up under long continued usage.

Another object of my invention is to simplify the construction and the assembly of the lock mechanism.

A further object is to provide a catch member of a springy resilient material, different from the material used for the extension sections.

An additional object is to utilize ears struck up from one extension section to secure the catch member thereto.

With these and other objects and advantageous features in view, the invention consists of novel arrangements of parts more fully disclosed in the detailed description following, in conjunction with the accompanying drawings, and more particularly set forth in the appended claims.

In the drawings:

Fig. 1 is a top plan view of the extension device in folded position;

Fig. 2 is a view similar to Figure 1, showing the extension device in unfolded position;

Fig. 3 is a side view corresponding to Figure 2;

Fig. 4 is a section on the line 4—4 of Figure 3;

Fig. 5 is a longitudinal section of the extension device in folded position; and

Fig. 6 is a transverse section on the line 6—6 of Figure 5.

It has been found desirable, in constructing extension devices, to provide a catch member of different material than the material used for the extension sections, thus permitting use of a soft material such as silver for the sections, and a hard, springy steel for the catch member. I have utilized a U-shaped catch member of this type, and have struck up ears from the stock of one extension section to fold over the base of the catch member to rigidly secure the catch member to its sec-

tion; and the following is a detailed description of a preferred construction embodying the principles of my invention.

Referring to the drawings, 10 designates the extension device as a whole, the extension device including a channel shaped cover section 11, an intermediate section 12 hinged thereto, and an end section 13 hinged to the intermediate section and adapted to fold with the intermediate section into the cover section between the side walls 14, 15 thereof. The strap ends 16, 17 are respectively secured to the sections 11, 13 by an adjustable clamp 18 and a pivot connection 19.

The intermediate section 12 has a latch opening 20 centrally positioned adjacent its hinge connection to the cover section, and the end section has a catch 21, U-shaped in cross section, with a base 22, and resilient sides 23, 24 adapted to snap into engagement with the sides of the opening 20 when the sections are folded together; the ends of the sides 23, 24 are rounded as shown in Figure 6.

The catch 21 is preferably formed of hard, springy steel, and is rigidly secured to the end section by two ears 25, 26 struck up from the material of the end section and folded over the base 22 of the catch in abutting relation to lock the catch in position.

My improved construction therefore simplifies the assembly of the catch, since no riveting is required, and permits the use of a catch formed of hard, resilient material, in an extension device formed of the softer and more ductile decorative materials used in the jewelry art.

While I have described a specific embodiment illustrating my invention, it is obvious that desired changes in structure and in arrangement may be made, without departing from the spirit and the scope of the invention as defined in the appended claims.

I claim:

1. In an extension device for flexible bracelets, a plurality of sections hingedly connected to fold together, means for securing bracelet ends to the free ends of the end sections, a latch opening in one section, a cooperating resilient U-shaped catch on one of the end sections, and a member struck from the stock

of the said end section and folded over the base of said catch to lock said catch to the said end section.

2. In an extension device for flexible bracelets, a plurality of sections hingedly connected to fold together, means for securing bracelet ends to the free ends of the end sections, a latch opening in one section, a co-operating resilient U-shaped catch on one of the end sections, and aligned ears struck from the stock of the said end section and folded over the base of said catch to lock said catch to the said end section.

In testimony whereof I affix my signature.
15 SIDNEY J. BERTHERMAN.
